UNITED STATES PATENT OFFICE.

HAMPTON M. SMITH, OF GREENVILLE, SOUTH CAROLINA.

LOOM HARNESS STOP MOTION.

1,420,390.

Specification of Letters Patent. Patented June 20, 1922.

Application filed March 15, 1922. Serial No. 543,936.

To all whom it may concern:

Be it known that I, HAMPTON M. SMITH, a citizen of the United States, residing at Greenville, in the county of Greenville and 5 State of South Carolina, have invented certain new and useful Improvements in Loom Harness Stop Motions, of which the following is a specification, reference being had to the accompanying drawings.

10 This invention relates to stop motions for looms, and particularly to a motion designed to stop the loom upon the drop of a harness frame, either due to the dropping of a supporting strap, jack or wire.

15 The general object of the invention is to provide a device of this character which is very simple and which is particularly adapted to a Draper loom.

20 A further object is to provide a device of this character including a pivoted arm normally held in a raised position by a spring and including means whereby the spring may be readily tensioned so as to normally hold the pivoted arm in a raised position 25 to permit the pivoted arm to drop upon the descent of any one of the harness frames.

Another object is to provide a mechanism 30 of this character which will accommodate the shipper lever ordinarily found on Draper looms.

Other objects will appear in the course of the following description.

My invention is illustrated in the accompanying drawings, wherein:—

35 Figure 1 is a perspective view of my harness stop motion;

Figure 2 is an enlarged fragmentary side elevation thereof and showing it in conjunction with the usual feeler finger and box 40 below which the feeler finger moves;

Figure 3 is a side elevation of the guide for the blade of the device.

Referring to these drawings, 10 designates a support having a base 11 upon which the support 45 is adjustably mounted by means of the screws 12. The upper end of this support 10 has a horizontally extending head 13. One end of this head is so formed as to pivotally support a lever 14. Preferably one end 50 of this head is formed with the upwardly extending lugs 15 through which passes a pivot bolt 16 upon which the lever 14 is mounted. The opposite end of the head 13 is upwardly extended and vertically slotted 55 to form a guide 17 between which the ex-

tremity 18 of the lever 14 operates. The head 13 adjacent the guide 17 is slotted, as at 19, and the lever is formed with a downwardly bowed portion 20 which operates through this slot. The opposite end of the lever is pivotally connected to a blade 21, the upper end of which is inclined, as at 22.

Attached to the head 13 adjacent the lugs 15 is an angular arm 23, the vertical portion of which extends through the head and is 65 screw-threaded and held in adjusted position by means of nuts 24. By this means the arm may be adjusted vertically. The extremity of the arm is engaged with an eye on one end of a coiled contractile spring 25, the 70 opposite end of which is formed with a hook adapted to engage over the lever 14 and specifically in the notches 26. By providing a plurality of notches, the spring may be shifted so as to shift its upper end toward 75 or from the pivot bolt 16 and thus more or less adjust the tension of the spring, and by adjusting the nuts 24 it is obvious that the arm 23 may be moved up or down and thus further adjust the tension of the spring. 80 The blade 21 extends up through the slot 26 of a guide bracket 27, the shank of this guide bracket being inclined with reference to the body of the bracket and being attached to one of the girths 28 below which 85 the feeler bar 29 oscillates in the usual manner. This feeler bar may be constructed in any suitable manner, but in the Draper loom this feeler bar consists of a flat, horizontally disposed plate which oscillates laterally below the girths. Normally the upper end 90 of the blade 21 is below the plane of oscillation of the feeler bar 29, but if any one of the harness frames 30 should fall through the breaking of a harness strap, wire, jack 95 or hook, the corresponding frame will drop downward at one or both ends and its weight will depress the forward end of the lever, as illustrated in dotted lines in Figure 2, raising the blade so that the blade will be 100 disposed in front of the feeler bar, preventing its operation and stopping the loom by the ordinary stop mechanism thereof.

It will be understood, of course, that there are two girths 28 which guide the ordinary drop members which receive the warp threads. This feeler bar 29 is vibrated by any suitable mechanism and when impeded in its free oscillating movement by the interposition of one of the drop members or the 110

free end of the blade 21, it, through mechanism not necessary to state, releases the shipper lever and stops the loom.

It will be seen that this mechanism is very simple and may be very cheaply made. The coiled spring 25 is an ordinary spring which may be easily replaced at any time in case its tension relaxes or may be easily adjusted at any time so that the lever 14 is just urged 10 upward by a force sufficient to hold it in this position but which is not sufficient to hold it up upon the dropping of one of the frames thereon. The U-shaped bend 20 made in the lever 14 accommodates the usual shipper rod 15 31 which, in the Draper loom, extends transversely of the loom forward of the harness frames and for which accommodation must be made.

I claim:—

20 1. A loom harness operated stop motion including a supporting member, a lever pivoted on the supporting member intermediate its ends, means urging one end of the lever downward, means for limiting the upward 25 movement of this end, and an upwardly extending blade pivoted to that end of the lever adjacent the urging means and adapted to be disposed adjacent a feeler.

2. In a loom harness operated stop motion, 30 a supporting member having a horizontally disposed head, a lever pivoted upon the head, a bracket carried up on the head and extending beneath one end of the lever, a coiled contractile spring between the bracket and 35 the lever, a stop motion actuating blade pivoted to this end of the lever, and a slotted member carried upon the head between which the other end of the lever operates, this last named end of the lever having a U- 40 shaped bend to accommodate the shipper rod of a loom.

3. A harness stop motion of the character described including a supporting member having a horizontally disposed head, one 45 end of the head being formed with upwardly

extending lugs, the opposite end of the head having a vertically slotted portion and the head being longitudinally slotted adjacent the vertically slotted portion, a lever pivoted between said lugs, the lever adjacent one end being formed to provide a depending, U-shaped bend operating through said last named slot, the extremity of the lever being extended to operate through the vertical slot, the opposite end of the lever carrying an upwardly extending blade, a bracket mounted upon the head and extending below the same and toward the blade, and a coiled contractile spring engaging one end of the bracket and at its other end engaging the lever between the pivotal point of the lever and the blade.

4. A harness stop motion of the character described including a supporting member having a horizontally disposed head, one end of the head being formed with upwardly extending lugs, the opposite end of the head having a vertically slotted portion and the head being longitudinally slotted adjacent the vertically slotted portion, a lever pivoted 65 between said lugs, the lever adjacent one end being formed to provide a depending, U-shaped bend operating through said last named slot, the extremity of the lever being extended to operate through the vertical slot, the opposite end of the lever carrying an upwardly extending blade, a bracket mounted upon the head and extending below the same and toward the blade, a coiled contractile spring engaging one end of the bracket and at its other end engaging the lever between 70 the pivotal point of the lever and the blade, and a guide bracket having a slot through which the blade passes, said guide bracket having means whereby it may be attached to 75 one of the side plates of a drop member box.

In testimony whereof I hereunto affix my signature.

HAMPTON M. SMITH.
